UNITED STATES PATENT OFFICE.

EDWARD D. BAKER, OF MARISSA, ILLINOIS.

COIN-CONTROLLED GASOLINE PUMP.

Application filed February 21, 1924. Serial No. 694,342.

To all whom it may concern:

Be it known that EDWARD D. BAKER, a citizen of the United States, residing at Marissa, in the county of St. Clair and State of Illinois, has invented certain new and useful Improvements in Coin-Controlled Gasoline Pumps, of which the following is a specification.

This invention relates to coin controlled pumps especially adapted to be used for dispensing gasoline or motor oil and it consists in the novel features hereinafter described and claimed.

An object of the invention is to provide a pump which is normally retained in a locked or inoperative position, there being provided within the body of the pump electric means and instrumentalities adapted to unlock and release the operative parts of the pump, upon the insertion of a coin in the casing, whereby the customer or purchaser may manipulate the pump and draw or extract from the same a quantity of the gasoline or oil which is the equivalent in value of the coin which has been inserted in the body of the pump and thereby makes it possible to dispense the gasoline or oil without the attention of the salesman or attendant to conduct and supervise the operation and manipulation of the pump.

The pump will require very little attention and its use eliminates the service of an attendant. The pump may be used to advantage in rural districts and small towns and other places where it is difficult to obtain gasoline at night. The pump is at all times in condition to dispense the gasoline and may be used to advantage at garages and similar places where help is scarce in that the dispensation of the gasoline may be continued by the purchaser and without the services of an attendant or assistant. The pump may be made in various sizes, some of them of a size adapted to dispense gasoline and others of appropriate size for the dispensation of machine or motor oil.

In the accompanying drawings:

Figure 1 is a side elevation of the pump showing the casing thereof in section.

Figure 2 is a fragmentary vertical transverse sectional view of the pump.

Figure 3 is a horizontal sectional view of the pump cut on the line 3—3 of Figure 1.

Figure 4 is a fragmentary detail sectional view of the upper portion of an oil cylinder used in the pump.

Figure 5 is a similar view of the lower portion of the oil cylinder.

Figure 6 is a fragmentary perspective view of a locking lever used in the pump. 60

Figure 7 is a fragmentary perspective view of the electric circuit closing device used in the pump.

Figure 8 is a transverse sectional view of a coin chute used in the pump and taken on 65 the line 8—8 of Figure 1.

Figure 9 is a similar view of the coin chute taken on the line 9—9 of Figure 1.

Figure 10 is a fragmentary detail view of the coin chute, the circuit closing mechanism 70 and illustrating a coin in position and serving as a circuit closure.

The pump comprises a casing 1 which is mounted upon a pedestal 2 adapted to be positioned upon a suitable foundation, not 75 shown.

An oil supply pipe 3 leads through the pedestal 2 and connects with the lower end of a cylinder 4 which is positioned within the lower portion of the casing 1. A piston 80 5 is slidably mounted in the cylinder 4 and is provided with valve controlled ports 6 which pass transversely therethrough. A piston rod 7 is connected at its lower end with the center of the piston 5 and passes 85 through the top side of the cylinder 4. The upper end of the rod 7 is pivotally connected with a pitman rod 8 and the upper end of the said rod 8 is connected with a pin 9 which is carried in a block 10. 90

A coin chute 11 penetrates the upper portion of the casing 1 and the said chute is oblong in transverse section. At the point where the chute penetrates the casing, the longer transverse dimension of the chute is 95 vertically disposed and at the interior of the casing, the chute is twisted so that its longer transverse dimension is horizontally disposed. The chute 11 is downwardly and inwardly inclined within the casing 1 and 100 the horizontally disposed portion thereof is indicated at 12 in the drawings. A cam disk 14 is journalled in the casing 1 with the upper portion of its periphery at the delivery end of the chute 11 and the said cam 105 disk carries upon its periphery a pin 13 which is normally disposed at the delivery end of the chute 11 but spaced therefrom.

Spaced terminals 15 are located at the upper portion of the periphery of the disk 110 14 and in the vicinity of the coin delivery end of the chute 11. Electric wires 16 and

17 are connected with the terminals 15 and the wire 16 leads to batteries 18 located in the casing 1 and the wire 17 leads to magnets 19 located in the casing 1. A wire 20 connects the magnets with the batteries 18. The upper portion of the coin chute 11 is provided at its lower side with an opening 12^a which is less in transverse breadth than the transverse breadth of the coin which is to be passed through the chute 11 and which will operate the unlocking mechanism of the pump. Therefore if a spurious coin or a slug is inserted in the chute 11 and is of less transverse breadth than the breadth of the required coin, the said spurious coin or slug will fall from the chute 11 through the opening 12^a, edgewise and deposit in the lower portion of the casing 1 without operating the pump releasing mechanism.

20 The horizontal portion 12 of the chute 11 is provided at its lower side with an opening 12' which is less in transverse breadth than the transverse breadth of the prescribed coin which is to be used to operate the lock releasing mechanism. Therefore if a spurious coin or a slug of improper transverse dimension is inserted in the coin chute 11 and moves over the opening 12^a, the said spurious coin or slug will fall sideways through the opening 12' in the horizontal portion 12 of the coin chute 11 and deposit in the lower portion of the casing 1 without operating the lock releasing mechanism of the pump.

25 When a coin of proper denomination, as for instance, a twenty-five cent piece, is inserted in the coin chute 11, it rolls down the said chute and slides along the horizontal portion 12 thereof and passes out of the delivery end of the chute 11 and strikes the pin 13 upon the periphery of the disk 14. At the same time, the opposite side portions of the said prescribed coin come in contact with the ends of the terminals 15 and bridge the space between them and completes the electric circuit from the batteries 18 along the wires 16 and 17 to the magnets 19 which move a lever, hereinafter to be described, and said lever releases the disk 14 whereby 30 the said disk may be rotated by manually operable means, hereinafter to be described, and the pump is actuated to draw the oil through the pipe 3 into the cylinder 4 by the movement of the piston 5 therein and to 35 eject the oil from the cylinder by the movement of the said piston as will be explained hereinafter.

40 A valve 21 is located in the cylinder 4 and normally closes the upper end of the pipe 2. The valve 21 moves to an open position when the piston 5 moves in an upward direction and permits the oil to flow through the pipe 2 into the cylinder 1. Upon the downward stroke of the piston, the valve 21 closes and 45 the oil passes up through the ports 6 in the

piston 5 and enters the upper portion of the cylinder 4. A pipe 22 is connected with the top of the cylinder 4 and a check valve 23 is located at the lower end of the pipe 22. As the piston moves in an upward direction 70 in the cylinder 4, the valve 23 moves to an open position and the oil is forced upwardly into the pipe 22. An oil receptacle 24 is mounted upon the top of the casing 1 and receives the oil from the pipe 22. The said receptacle is provided at its side with a series of vertically arranged graduations 25 which indicate the number of gallons contained within the receptacle 24. A signal lamp 26 of conventional form is mounted upon the top of the receptacle 24, and the receptacle 24 is surrounded by a wire netting 27 which protects the said receptacle. A delivery pipe 28 is connected with the bottom of the receptacle 24 and is provided with a valve 29 which is normally closed. A handle lever 30 is connected with the stem of the valve 29 and is pivoted upon the casing 1. The pipe 28 is connected with a hose 31, the nozzle of which may be inserted in the receptacle 90 which is to receive the oil.

When the oil is forced out of the cylinder 4 it moves up along the pipe 22 into the receptacle 24 until the desired quantity has been accumulated in the said receptacle and 95 which may be ascertained by observing the graduations upon the scale 25 and comparing the same with the level of the oil in the receptacle 24. The nozzle of the hose 31 is then inserted in the receptacle which is to 100 receive the oil, and the purchaser pulls down the outer end of the lever 30 whereby the oil is permitted to drain out of the receptacle 24 through the pipe 28 and flow through the hose 31 into the said receptacle 105 which is to receive the oil.

The disk 14 is provided with a cam shoulder 32. A lever 33 is fulcrumed within the casing 1 and is provided with lugs 34 which normally bear against the shoulder 32 and hold the disk 14 against rotary movement. The outer end of the lever 33 is weighted as at 35 to hold the lugs 34 toward the periphery of the disk 14 so that they may engage the shoulder 32 when the shoulder 110 comes opposite the said lugs. The lugs 34 and the adjacent end portion of the lever 33 are disposed over the magnets 19. Consequently when the said magnets are energized by the passage of the electric current 115 over the wires 16 and 17 and as hereinbefore explained, the lugs 34 are removed away from the shoulder 32 and the disk 14 is free for rotation.

An arm 36 is fixed to the shaft of the disk 125 14 and is provided with a slot 37. The said arm and slot are normally horizontally disposed within the casing 1 and the block 10 hereinbefore described, is adjustably secured in the slot 37. The arm 36, block 10, rods 130

8 and 7, and the piston 5 have their combined weights applied to the axis of the disk 14 at one side thereof. Consequently when the coin slides between the terminals 15 and closes the circuit, the arm 36 swings down by gravity and this carries the coin from between the terminals 15 and the electric circuit hereinbefore described is interrupted or broken. At the same time, the shoulder 32 upon the disk 14 has been carried beyond the lugs 34 and when the lever 33 is released by the magnets 19, the lugs 34 move up and engage the periphery of the disk 14 at a point beyond the shoulder 32. Thus the locking mechanism of the pump is released but the parts are in position to automatically assume their locked relation after the pump has been manipulated to deliver the quantity of oil to the customer and as has been and will be further explained hereinafter. A gear wheel 40 is mounted upon the axis of the disk 14 and meshes with a gear wheel 41 mounted upon a shaft 42 journalled in the casing 1. The shaft 42 passes through the side of the casing 1 and carries at its outer end a crank handle 43. A holding pawl 44 is pivoted in the casing 1 and is adapted to engage between the teeth of the wheel 41 and hold the same against rotation in a reverse direction.

When the coin has been inserted in the coin chute and has completed the electric circuit to the magnets as hereinbefore described, and the turning movement of the disk 14 has been started, the purchaser grasps the crank handle 43 and turns the same whereby the intermeshing gear wheels 41 and 40 continue the rotation of the disk 14 which carries the arm 36 around with it and the rods 7 and 8 are moved longitudinally whereby the piston 5 is reciprocated in the cylinder 4 and the oil is pumped from the cylinder through the pipe 22 into the receptacle 24. Thus the oil is supplied from the cylinder to the receptacle 24 and it is drawn off from the receptacle 24 in the manner as hereinbefore described.

When the arm 36 completes one revolution, the lever 33 has been released by the magnets 19 and the lugs 34 come in contact with the shoulder 32 upon the disk 14 and the pump is locked in an inoperative condition.

Having described the invention, what is claimed is:

1. A dispensing pump comprising a casing, a receptacle mounted thereon, means for pumping liquid into the receptacle, means for drawing liquid from the receptacle, electric generators located in the casing and connected in open circuit with magnets, a coin chute arranged to deliver a coin to close the circuit, a disk located in the path of movement of the coin, means for locking the disk against turning movement and disposed in the field of the magnets, means connected with the disk for initially turning the disk when released, and manually operable means for completing the turning of the disk and to operate the pump to elevate the liquid into the receptacle.

2. A liquid dispensing pump comprising a casing, a receptacle mounted thereon, a pump located therein and arranged to deliver the liquid to the receptacle, means for drawing the liquid from the receptacle, batteries located in the casing and connected in open circuit with terminals and connected with magnets, a lever fulcrumed in the casing and having its free end disposed in the field of the magnets and provided with lugs, a coin chute leading into the casing and having its delivery end disposed toward the terminals of the electric circuit, a disk journalled in the casing and having a pin disposed opposite the delivery end of the coin chute, an arm fixed with relation to the disk and operatively connected with the pump, and means operatively connected with the disk and adapted to be manipulated exteriorly of the casing for rotating the disk.

In testimony whereof I affix my signature.

EDWARD D. BAKER.
